MARKING DEVICE

George F. Wittman, Dayton, Ohio

Application December 21, 1938, Serial No. 246,980

17 Claims. (Cl. 33—189)

This invention relates to fixtures which may be used in tool and machine shops for sheet metal work and particularly for work wherein it is necessary to locate a plurality of accurately spaced points and to punch holes at these located points or to use these points for layout of the outline of a lever or other odd shaped article of manufacture.

An object of my invention is to provide a machine wherein a sheet of metal may be accurately located with respect to a fixed point on the machine whereby a plurality of points can be located on the sheet and be accurately spaced with respect to each other.

Another object of my invention is to provide a machine wherein a sheet of metal can be accurately moved in a horizontal plane with respect to a locating point on the machine and be maintained in accurate position with respect to said point at all times by a three point system of location for said sheet.

A further object of my invention is to provide a machine wherein a plurality of holes may be accurately spaced one from the other and be accurately punched in one and the same operation.

A still further object of my invention is to provide a machine upon which accurate measurements may be made in any direction by moving a metal sheet in a horizontal plane with respect to a fixed point on the machine whereby layout of complicated levers and other odd shaped articles of manufacture may be initially layed out on a metal sheet.

A still further object of my invention is to provide a hand operated punch and die machine wherein punches and dies may be quickly and easily interchanged.

Further objects and advantages of the present invention will be apparent from the following description, reference being had to the accompanying drawings, wherein a preferred embodiment of the present invention is clearly shown.

In the drawings:

Fig. 1 is a front elevational view of my improved machine.

Fig. 2 is a perspective view of the base plate for my machine.

Fig. 3 is a view taken on line 3—3 of Fig. 1, and is partially in section and partially in elevation.

Fig. 4 is a cross sectional view taken on line 4—4 of Fig. 3.

Fig. 5 is a view showing a marking instrument. 55

In this invention my device consists of a base

plate 10, upon which all of the elements of my machine are supported. A vertically arranged supporting structure 11 is adapted to be attached to the base 10 of my machine by means of bolts 12 and 13. A horizontally extending bearing member 14 is formed as an integral part of the structure 11 and is provided with a drilled opening 15, which extends through the member 14 and provides the bearing for a drive shaft 16 which extends therethrough. The drive shaft 16 is provided with an eccentric portion 17 as an integral part thereof. A driving link 18 is positioned upon the eccentric 17. This link 18 provides the driving connection between the eccentric 17 and the driven mechanism of my machine. The drive shaft 16 is also provided with an enlarged portion 19, which portion in combination with the spacer washer 20 provides means whereby the link 18 is located horizontally upon the drive shaft 16. A bolt 21 extends into one end of the drive shaft 16 and a washer 22 is provided under the head of the bolt 21, the bolt and washer cooperating to retain the shaft 16 in position in the bearing 14.

A hand wheel 23 is positioned on the opposite end of the drive shaft 16 and is provided for driving the mechanism of my invention. The hand wheel 23 is retained upon this end of the drive shaft by means of bolt 24 and washer 25. The hand wheel is mounted upon the end 26 of the drive shaft in a free manner so that the wheel may turn without revolving the drive shaft during certain intervals of rotation. The hand wheel 23 is provided with an extending portion 27 on the rearward side thereof. This portion 27 is cut away in such a manner as to provide an extending segment 28 which projects beyond the surface of the portion 27, and is adapted to co-act with a similar segment on the enlarged portion 19 of the drive shaft 16. The enlarged portion 19 of the drive shaft 16 is also cut away in such a manner as to provide an extending segment 29 which is adapted to co-act with the segment 28. The segment 29 has a larger portion cut away than is replaced by the segment 28, when the two segments are in operative position so that a gap 30 is provided between the two segments. The function of the arrangement of the segments 28 and 29 and the eccentric 17 will be more fully explained hereinafter.

The link 18 is joined to a block 31 by means of a pin 32 which extends through the link 18 and block 31 thereby providing a pivotal point of connection through which the block 31 is driven. The block 31 is provided with an ex-

tending portion 32a which is dove-tail shaped and which slidably engages a dove-tail shaped notch 33 in support member 34. The support member 34 is attached to the structure 11 by means of a bolt 35 and provides one of the guide members for the operating mechanism of my invention. An adjusting screw 36 is provided, one end of which is threaded into the bottom face of the block 31 and the opposite end is threaded into the top face of the block 37. This screw has a right hand thread 38 on the upper end thereof and a left hand thread on the lower end 39. These screw threads 38 and 39 provide means for adjusting the vertical position of the blocks with respect to each other and with respect to the base plate of my machine. Lock nuts 40 and 41 are provided on the respective screw threads for locking the same in position after the desired adjustment of the blocks has been obtained.

The block 37 is provided with a horizontal slot 37b in which a hardened steel block 42 is slidably positioned. An enlargement of the slot 37b is provided below the bottom face of the block 42 in which a punch adaptor 43 is adapted to be positioned. This adaptor 43 carries a punch 44 of any suitable dimension, size or shape. The block 37 is dove-tailed into a guide member 45 which permits vertical movement of the block 37 in the slot 37a in the same manner as that of block 31 in slot 33. The supporting guide member 45 in which the slot 37a is positioned is attached to the structure 11 by means of a bolt 46.

35 A punch guide member 50 is provided for the punch 44 in a supporting member 51 which extends from the structure 11. The supporting member 51 is attached to the structure 11 by means of a bolt 52. The punch guide member 50 is loosely positioned within the support member 51 so as to permit easy removal of the punch guide member. The arrangement of the punch adapter 43 and the punch adapter retaining block 42 is such as to permit an easy removal 45 of the punch 44 from the guide member 50 and the supporting block 37. The hardened steel block 42 is in sliding engagement with the slot 37b in the carrying member 37. By removing the block 42 in a horizontal direction the slot 37b 50 is opened thereby creating a space into which the punch member 44 may be lifted vertically and into the opening created by the removal of the block 42. This vertical movement of the punch 44 is sufficient to permit the end of the punch 44 55 to be withdrawn from the punch guide member 50, whereby the punch 44 and the adapter 43 may then be slid in a horizontal direction from the retaining slot to permit removal thereof.

60 The base member 10 is adapted to support a plate 60 upon which the sheet metal member or the work is adapted to be placed when points of location are to be determined. This plate 60 has two adjacent edges thereof 61 and 62 finished at an accurate 90 degree angle. A vertically extending wall 63 is attached to the edge 62 of the plate 60 and a second vertically extending wall 64 is attached to the edge 61 of the plate 60. These walls may be separate members as shown on the drawings or they may be formed 65 as an integral part of the plate 60. If the walls 63 and 64 are formed as integral parts of the base 60 then the faces 65 and 66 are finished at an accurate 90 degree angle. If they are removable as disclosed in the drawings the securing 70 of the walls to accurately finished faces of

the plates 60 will automatically arrange the inner faces of the walls 63 and 64 at an accurate 90 degree angle. It may also be desirable to removably attach the walls 63 and 64 to the plate 60 and attach them to the plate 60 each time my device is to be used. Under these conditions however, it would be necessary to accurately determine the angularity of the walls with respect to each other and with respect to grooves provided in the base plate which are 10 hereinafter more fully described.

15 The base plate 60 is provided with one set of parallel grooves 70 spaced equidistant from each other. These grooves are accurately positioned in parallel relation with respect to each other and with respect to the edge 62 of the base plate 60. A second set of grooves 71 are provided in the base plate 60 and are also equidistantly spaced from each other. These grooves 71 are accurately arranged in parallel relation with each other and with respect to the edge 61 of the base plate 60. It will thus be seen I have provided a surface plate member with a plurality of equidistantly spaced parallel grooves positioned in alternate directions on the base plate which are 25 arranged at accurate 90 degree angles with respect to each other and with respect to the accurately faced edges 61 and 62 of the base plate 60.

30 A plurality of end measuring rods, each having a determined length, are provided and are adapted to be positioned within the grooves 70 and 71 of the base plate. These rods are of various determined lengths and are indicated as groups of rods at 73, 74 and 75. It will be noticed that in each groove in which measuring rods have been placed in my device that a sequence of rods are used thereby providing means whereby various combinations of rods having different determined lengths may be used 35 to obtain various dimensions. One of the rods of each of the groups 73, 74 and 75 is a variable length rod and is what is known on the commercial market as an inside micrometer. The variable length rod can be positioned in any position within the group, but is preferably placed at one end as indicated in the drawings at 73a, 74a and 75a.

40 Within the base plate 60 there is provided a screw thread member 76 which is provided with an extension 77 extending upwardly into the plate 60. A die member 78 is removably positioned within an opening provided in the base plate 60 and is supported by the extension 77 of the screw thread member 76. The member 76 provides an adjustment of the top surface of the die 78 so that this surface will be in contact with the bottom face of the sheet metal work 80 positioned in my machine. A lock nut 79 is provided on the screw thread member 76 for retaining the member in position after adjustment of the top surface of the die 78 has been obtained.

45 My device as heretofore described is particularly useful in the novel way in which it may be used in order to obtain and establish locations 55 of various points upon a sheet of metal which has been placed in my device. Heretofore when laying out levers or other odd shaped pieces of manufacture it has been necessary for workmen to use many different types of tools for determining locations of holes and radius points. Many times locations for holes and radius points are positioned at odd angles which make it difficult to obtain an accurate measurement and necessitated the use of articles such as sine bars, 70 75

height gauges, gauge blocks, angle irons, and many other precision instruments. By the use of my device it is possible to easily and accurately determine the location of any hole or radius point 5 with respect to any other hole or radius point and to punch the hole at the located point without removing the work from the machine.

In my invention when my device is to be used for the purpose of laying out a lever and for 10 positioning holes therein the punch, as indicated at 44, is removed and a sharp pointed prick punch 44a is placed in position. By loosening the lock nuts 40 and 41 on the adjusting element 36 it is possible to turn the adjusting member 15 36 by hand or by the use of a small wrench. Movement of this element 36 will cause the carrier block 37 to move downwardly and carry the prick punch 44a into contact with the sheet metal work 80, thereby providing means for indicating a point on the work after it has been once 20 established. The point of location established by the fixed relation position of punch 44a may be called a primary point of location from which all other points of location may be established 25 by moving the work with respect to the primary point of location and controlling the measured movement of the work by the series of end measuring rods 73, 74 and 75.

In order to use my invention for purposes of 30 layout work of levers and other odd shaped articles of manufacture a sheet of metal, such as I have indicated at 80, is provided with two adjacent edges thereof which have been accurately machined to an angle of 90 degrees. These edges 35 for purposes of illustration are indicated at 81 and 82. The sheet metal work is then placed upon the base plate 60 and below the punch 44 or prick punch 44a which ever is being used in my device at that particular time. The work 40 upon being placed under punch 44 or the prick punch 44a is provided with a primarily established point of measurement. The point which is taken as the primary point is not of particular importance since any one of the radius centers or centers for holes may be used as a 45 primary point and all others will then be established using that as the basis. Once the device has been positioned under the punch and a primary point of location has been established the 50 end measuring rods are positioned in the grooves 70 and 71. A sufficient number of rods are used to accurately fill the space in any one groove between the finished edge of the work 80 and a wall or edge of the base plate 60. In my invention I have used three series of end measuring rods which are located at 73, 74 and 75 respectively, upon the base plate 60. In each series 55 of end measuring rods there is one rod which is provided with an internal micrometer adjustment, this adjustable rod being indicated at 73a, 74a and 75a. These adjustable rods provide means for very accurately moving the work with respect to the punch 44. As heretofore stated, I have used three series of end measuring rods, 60 two of which will be positioned adjacent one of the finished sides of the work 80 and one adjacent the other finished adjacent side, which sides have been accurately finished to a 90 degree angle. The two series of measuring rods 74 and 75 are adjusted so that they are of equal length 65 thereby accurately spacing the ends thereof equidistantly from the wall 65 so that when the work 80 is placed upon the base plate 60 and the edge 82 of the work 80 is placed against the 70 ends of the rods 74 and 75 this edge 82 will be

parallel with respect to the grooves 70, positioned in the base plate, and with respect to the wall 65. The positioning of the work in this manner automatically places the edge 81 of the work 80 at a right angle to the grooves 70 and parallel 5 to the grooves 71 and the wall 64. The series of measuring rods indicated at 73 accurately control the movement of the work 80 with respect to the wall 64.

The walls 64 and 65 provide means whereby 10 the end measuring rods may be always definitely positioned with respect to the punch 44, the primary point of location, since the rods abut these walls at all times when measurements are being made. By the arrangement and use of three 15 measuring rods in the manner I have disclosed in my application I provide means whereby the work 80 may at any time be removed from the base plate 60 and be replaced without the necessity of reestablishing the perfect parallel relation of the finished sides 81 and 82 of the work 80 with respect to the grooves 70 and 71 and the walls 64 and 65.

It may readily be seen that if the group of 20 measuring rods 73 is either increased or decreased in length a second dimension may be obtained from the primary point which has previously been established on the work 80, and will be in alignment with and in a perfect straight line from the previously established point. If 25 the groups of measuring rods 74 and 75 are increased in length in exact amounts a third dimension may be obtained in a straight line from the primary point of location but which will be at right angles to that which was obtained by 30 that movement of the work 80 caused by movement of the group of rods 73. It will be observed however that the rods 74 and 75 must be kept in perfect like adjustment at all times. This is necessary in order to keep the work 80 40 in perfect squared relationship with the grooves 70 and 71 and the walls 64 and 65 of the base plate 60. It may also be seen that if the groups of rods 74 and 75 are increased in length at the same time that the group of rods 73 is increased, 45 that an angular dimension may be obtained from the primary point of location. After the initial dimension has been established on the work 80 and the rods 73, 74 and 75 have been initially set for their length any dimension desired, from 50 one point to another upon the work, can be obtained and the dimension will be the same as the dimension which appeared upon a drawing from which the layout of the lever is being made, it being merely necessary to increase the length 55 of the rod an amount equal to that called for on the drawing.

My device provides a means for not only laying out work such as levers and other odd shaped articles of manufacture but also provides 60 a means whereby, after points of location have been established upon work 80, holes or other suitable openings may be punched in the work without further movement and without removing the work from my device.

The punch that I have provided in my device and the arrangement of the manner in which I retain my punch in the carrier block 37 is such that the punch 44 may be quickly and easily changed to provide for punching various sized 70 holes or odd shaped openings. My device thus becomes not only a device for establishing measurements but is also a punch and die machine upon which holes may be accurately located and after being located may be punched in the sheet 75

metal without removing the work from the machine.

In my device I have provided a means for obtaining power for driving the punch through the metal sheet of work 80. This power developing device consists of the hand wheel 23 and the segment 28 which is a part thereof and the segment 29 which is mounted upon the drive shaft 16 of my device. The segment 28 co-acts with the segment 29, which is positioned on the drive shaft 16, in such a manner that when the hand wheel is rotated in a clock-wise direction, as viewed in Fig. 4, the shaft 16 will also be rotated causing the eccentric 17 to move the punch mechanism downwardly against the work 80. When the punch 44 has touched the work 80 the hand wheel may then be turned in a counter-clockwise direction, the gap shown at 30 in Fig. 4, permitting this reverse rotation. The hand wheel may then be rotated quickly in a clock-wise direction until the segments 28 and 29 engage, at which time the punch 44 will be driven through the sheet metal work 80.

It is thus seen that the device as disclosed in my application provides an improved form of punch and die machine and particularly improved in that I am able to obtain accurate measurements and locations of points on a sheet of metal while the sheet is in the machine and with a greatly reduced amount of effort than it has heretofore been necessary to put forth to establish locations of points.

While the embodiment of the present invention as herein disclosed, constitutes a preferred form, it is to be understood that other forms might be adopted, all coming within the scope of the claims which follow.

What is claimed is as follows:

1. An apparatus for determining points of location on a metal sheet which comprises a flat base plate upon which work can be positioned, a series of parallel grooves in said base plate, a second series of parallel grooves in said base plate arranged in an angular position of 90 degrees with respect to said first mentioned series of parallel grooves, measuring rods adapted to be positioned in said grooves, means on said base plate against which said rods abut when in position in said grooves, marking means positioned adjacent said base plate, and means for varying the length of said measuring rods whereby an element of work positioned on said base plate can be moved with respect to said marking means whereby a plurality of points of location can be accurately determined.

2. An apparatus for determining points of location on a metal sheet which comprises a flat base plate upon which work can be positioned, walls extending upwardly from said base plate and along at least two sides thereof, said walls having an angular position of 90 degrees with respect to each other, a series of parallel grooves in said base plate arranged in an angular position of 90 degrees with respect to one of said vertically extending walls, a second series of parallel grooves in said base plate arranged in an angular position of 90 degrees with respect to a second of said vertically extending walls, a measuring rod adapted to be positioned in a groove of one of said sets of parallel grooves, two measuring rods adapted to be positioned in grooves of said other set of parallel grooves, said three measuring rods providing a three point system of location for an element of work positioned on said base plate, marking means positioned adjacent

said base plate, and means for varying the length of said measuring rods for causing movement of the element of work with respect to said marking means whereby a plurality of points of location are determined.

3. A device for measuring distances on a metal sheet which comprises a surface plate, adjacent extending sides on said plate, means on said plate adapted to position a metal sheet on said plate in a predetermined position, said means including a variable length rod adapted to be positioned between one of the sides of a sheet placed on said plate and one of said sides of said plate, two variable length rods adapted to be positioned between an adjacent side of a sheet placed on said plate and said other of said sides of said plate, marking means positioned adjacent said plate for providing a point of determination, said means for positioning the metal sheet providing the means for moving the sheet relative to said marking means, and means for causing measured movement of the sheet upon said plate with respect to said marking means.

4. A device for measuring which comprises a surface plate, measuring devices, means in said surface plate for positioning said measuring devices thereupon in a determined angular position with respect to each other, means positioned adjacent said surface plate for providing a point of determination, said measuring devices being arranged to position an element to be worked upon in a definite angular position with respect to said primary point of determination, said measuring devices having adjustable lengths to cause movement of the element to be worked upon with respect to said point of determination.

5. A device for locating the position of holes in a metal sheet which comprises a flat base plate upon which an element of work is adapted to be positioned, a series of parallel grooves in said base plate, a second series of parallel grooves in said base plate arranged in an angular position of 90 degrees with respect to said first mentioned series of parallel grooves, measuring rods positioned in said grooves for positioning an element of work on said base plate, means on said base plate against which said rods can abut when in position in said grooves to establish location of said rods, a marking punch positioned above said base plate, and means to cause said marking punch to pierce the element of work which is positioned on the base plate thereby establishing the position of a hole in the work.

6. A device for measuring which consists of a flat plate having two sets of parallel grooves arranged at an angle of 90 degrees with respect to each other, adjacent end walls for said plate, said walls arranged at an angle of 90 degrees with respect to each other and each of said walls arranged at an angle of 90 degrees with respect to one set of parallel grooves in said plate and parallel to said other set of parallel grooves, marking means positioned above said base plate, measuring rods of determined length positioned in said grooves, one end of said rods abutting said walls, said rods providing means for positioning an element of work in a definite position on said plate with respect to said marking means, and means for causing engagement of said marking means against the element of work to establish a point of location thereon.

7. An apparatus for determining points of location on a metal sheet which comprises a flat base plate, said base plate having vertically extending walls along at least two sides thereof,

5 said walls having a determined angular position with respect to each other, measuring rods for positioning an element to be worked upon in definite angular positions with respect to said walls, means in said base plate for retaining said rods in a definite angular position with respect to said vertically extending walls, said walls providing means to position one end of said rods, marking means positioned above said base plate, 10 and means to cause said marking means to engage an element of work adapted to be positioned on said base plate to establish a point of location thereon.

15 8. An apparatus for determining points of location on a metal sheet which comprises a flat base plate, said base plate having vertically extending walls along at least two sides thereof, said walls having an angular position of 90 degrees with respect to each other, measuring rods for 20 positioning an element to be worked upon in definite angular positions with respect to said walls, means in said base plate for retaining said measuring rods in an angular position of 90 degrees with respect to at least one of said vertically extending walls, said walls providing means 25 to position one end of said rods, marking means positioned above said base plate, and means to cause said marking means to engage an element of work adapted to be positioned on said base 30 plate to establish a point of location thereon.

35 9. An apparatus for determining points of location on a metal sheet which comprises a flat base plate, said base plate having vertically extending walls along at least two sides thereof, said walls having a determined angular position with respect to each other, measuring rods for 40 positioning an element to be worked upon in definite angular positions with respect to said walls, means in said base plate for retaining said rods in a definite angular position with respect to said vertically extending walls, said walls providing means to position one end of said rods, marking means positioned above said base plate for providing a point of determination, said 45 measuring rods having definite measurable positions with respect to said vertically extending walls and said marking means whereby a plurality of points of location can be accurately determined on an element of work positioned on 50 said base plate.

55 10. An apparatus for determining points of location on a metal sheet which comprises a flat base plate upon which work can be positioned, a series of parallel grooves in said base plate, a second series of parallel grooves in said plate arranged in an angular position of 90 degrees with respect to said first mentioned series of parallel grooves, a measuring rod adapted to be positioned in a groove of one of said sets of parallel grooves, 60 two measuring rods adapted to be positioned in grooves of said other set of parallel grooves, means on said base plate against which said rods can abut when in position in said grooves, said three measuring rods providing a three point system of location for an element of work on said base plate, marking means positioned adjacent said base plate, and means for varying the length of said measuring rods whereby the element of work can be moved with respect to the marking 65 means to establish a plurality of points of location on the element of work.

70 11. In a device of the character described, a surface plate, measuring devices, grooves in said surface plate for positioning said measuring devices thereupon in a determined angular posi-

tion with respect to each other, and means adjacent said plate against which said measuring devices can abut to establish primary location of said devices.

75 12. In a device of the character described, a surface plate, a series of parallel grooves in said plate, a second series of parallel grooves in said plate arranged at an angular position of 90 degrees with respect to the first mentioned series of parallel grooves, a measuring device adapted to be positioned in one of said first mentioned series of parallel grooves, a second and a third measuring device adapted to be positioned in two of said second mentioned series of parallel grooves, said measuring devices providing means adapted to 10 position an element of work upon said plate.

15 13. In a device of the character described, a surface plate, a series of parallel grooves in said plate, a second series of parallel grooves in said plate arranged at an angular position of 90 degrees with respect to the first mentioned series of parallel grooves, a measuring device adapted to be positioned in one of said first mentioned series of parallel grooves, a second and a third measuring device adapted to be positioned in two of said second mentioned series of parallel grooves, each 20 of said measuring devices having an adjustable length, said measuring devices providing means adapted to 25 position an element of work upon said plate.

30 14. In a device of the character described, a surface plate, a series of parallel grooves in said plate, a second series of parallel grooves in said plate arranged at an angular position of 90 degrees with respect to the first mentioned series of parallel grooves, a measuring device adapted to be positioned in one of said first mentioned series of parallel grooves, a second and a third measuring device adapted to be positioned in two of said second mentioned series of parallel grooves, 35 and means adjacent said plate against which said measuring devices can abut to establish primary location of said devices whereby said measuring devices provide means adapted to position 40 an element of work upon said plate.

45 15. A device for locating the position of holes in a metal sheet which comprises a surface plate upon which an element of work is adapted to be positioned, measuring devices for positioning an element of work on said surface plate, grooves in 50 said surface plate for positioning said measuring devices thereupon in a determined angular position with respect to each other, means adjacent said plate against which said measuring devices can abut to establish primary location of said 55 devices, a marking punch positioned above said surface plate, and means to cause said marking punch to pierce the element of work which is positioned on the surface plate thereby establishing 60 the position of a hole in the work.

65 16. A device for measuring distances on a metal sheet which comprises a surface plate, adjacent extending sides on said plate, means on said plate adapted to position a metal sheet on said plate in a predetermined position, said means including a variable length rod adapted to be positioned between one of the sides of a sheet placed on said plate and one of said sides of said plate, two variable length rods adapted to 70 be positioned between an adjacent side of a sheet placed on said plate and said other of said sides of said plate, marking means positioned adjacent said plate for providing a point of determination, said means for positioning the metal sheet pro- 75

viding the means for causing measured movement of the sheet.

17. An apparatus for determining points of location on a metal sheet which comprises a flat base plate upon which work can be positioned, a series of parallel grooves in said base plate, a second series of parallel grooves in said base plate arranged in an angular position of 90 degrees with respect to said first mentioned series of 10 parallel grooves, measuring rods adapted to be

positioned in said grooves, means for positioning said rods in said grooves, marking means positioned adjacent said base plate, and means for varying the length of said measuring rods whereby an element of work positioned on said base plate can be moved with respect to said marking means whereby a plurality of points of location can be accurately determined.

GEORGE F. WITTMAN. 10
